PATIO SHELTER

George Bruce Anderson, 3015 McKillop Road,
Oakland, Calif.

Filed Jan. 24, 1963, Ser. No. 73,299

Term of patent 3½ years

(Cl. D13—1)

FIG. 1 is a side elevational view of a patio shelter showing my new design;

FIG. 2 is a top plan view of the patio shelter of FIG. 1;

FIG. 3 is a partially broken away view of the bottom of the patio shelter of FIG. 3 illustrating the support ribbing and the reed covering.

I claim:

The ornamental design for a patio shelter, as shown.
